RECORDING AND REPRODUCING APPARATUS

Willis S. Fridell, Washington, D. C., assignor to
 Thomas A. Edison, Incorporated, West Orange,
 N. J., a corporation of New Jersey

Application August 6, 1931, Serial No. 555,468

10 Claims. (Cl. 274—34)

This invention relates to recording or reproducing mechanism and more particularly to recording or reproducing mechanism adapted to be used on cylinder phonographs such, for example, as any of the well known makes of dictating machines.

It is an object of this invention to provide mechanism of the class described which is so constructed and arranged that considerable variation in the size of records being used may be permitted without interfering with the efficiency of the recording or reproduction.

It is a further object of this invention to provide apparatus of the class described in which the effect of the record being out of round or other irregularities in the record are substantially decreased.

It is still a further object of this invention to provide apparatus of the class described which shall be simple, rugged and unlikely to get out of order.

Still other objects and advantages of my invention will be apparent from the specification.

The features of novelty which I believe to be characteristic of my invention are set forth with particularity in the appended claims. My invention itself, however, both as to its fundamental principles, and as to its particular embodiments, will best be understood by reference to the specification and accompanying drawing, in which

Fig. 1 is a side elevation view of apparatus in accordance with my invention, and

Fig. 2 is an end elevation view thereof.

Referring now more particularly to the drawing,

1 indicates generically an electrical recording or reproducing unit, which may be of any desired type arranged to cause vibrations of the armature 2 in response to voice currents supplied to the unit or conversely to reproduce voice current when the armature 2 is vibrated by the record. The precise form or type of telephone unit employed forms per se no part of this invention and, in fact, it will be understood that my invention lends itself equally well to the mechanical type of recorder or reproducer utilizing a sound box and diaphragm.

50 In the present arrangement the telephone unit 1 is mounted by means of spacing blocks 4 upon the carriage 5 of the phonograph which carriage, as will be understood, moves with reference to the record 8.

55 The carriage 5 is provided with an extension

6 to which is secured a downwardly projecting bearing block 7 having portions of its lower extremity cut away to define the bearing arms 9 and 10, the said extension 6 and block 7 constituting a support for a floating weight 11. This floating weight terminates in ears 11a and 11b and is pivotally mounted upon pivots 12 and 13 carried by the arms 9 and 10 respectively, whereby it will be observed that the floating weight 11 is free to rotate about the pivots 12 and 13 as a 65 centre and may therefore swing up and down freely to take care of irregularities in the record due to various causes. To the opposite end of the floating weight 11 at point 15 there is pivoted one end of the stylus bar 14 carrying the stylus 70 16. The opposite end of the stylus bar 14 is connected to the lower end of link 3 as by means of pivot 17 passing through the lower end of link 3 and the end of stylus bar 14. The upper end of the link 3 is connected to the armature 2 of 75 the telephone unit, if an electrical unit is employed, or to the diaphragm if a sound box is employed.

The pivot or point of connection between link 3 and stylus bar 14 is made to coincide with the 80 line of pivots 12 and 13, and while I have shown the lower end of link 3 terminating in a forked portion, it will be understood that other forms of connection may be employed if desired so long as the connection between the link 3 and the 85 stylus bar 14 coincides with the line of pivots 12 and 13. The extension 6 and the bearing block 7 may be drilled or otherwise provided with an opening to permit passage of the link 3.

It will be seen that this construction permits 90 the floating weight 11 and the stylus arm 14 to rotate as a unit about the axis 12—13 without changing the position of the link 3. At the same time, however, the stylus bar 14 is free to rotate about pivot 15 in response to vibrations transmitted to it through the link 3 or in transmitting to the link 3 vibrations impressed upon the stylus 16 by the record. The floating weight 11, as will be understood, is provided with sufficient mass 95 so that it is not moved by vibrations of sound 100 frequencies, whereas it swings up and down to take care of irregularities in the record.

While I have shown the stylus bar 14 pivoted on the floating weight 11 at point 15, it will be understood that this is merely diagrammatic and 101 that the pivot 15 may be located at any suitable point upon the floating weight in accordance with the conditions required to be met.

While I have shown and described certain preferred embodiments of my invention, it will be un- 11

derstood that modifications and changes may be made without departing from the spirit and scope of my invention as will be understood by those skilled in the art.

5. I claim

1. In phonographic apparatus of the class described, a support, a floating weight pivotally mounted on said support for rotation, a stylus bar having one end pivotally secured to said floating weight remote from the pivot thereof, a translating device, and a link connected between said translating device and said stylus bar, the connection between said link and said stylus bar being pivotal and on a line substantially coincident with the axis of rotation of said floating weight.

2. In phonographic apparatus of the class described, a support, a floating weight pivotally mounted on said support for rotation, a translating device mounted on said support, and a stylus bar carrying a stylus adapted to engage a record, said stylus bar being connected at one end to said floating weight and at the other end to said translating device, and the connection between said stylus bar and said translating device being pivotal and on a line substantially coincident with the axis of rotation of said floating weight.

3. In phonographic apparatus of the class described, a support, a floating weight pivotally connected at one side to said support, a stylus bar having one end pivotally secured to said floating weight at a point offset from the pivot thereof, a translating device, and a pivotal connection between said translating device and said stylus bar on a line substantially coincident with the axis of rotation of said floating weight.

4. In phonographic apparatus of the class described, a support, a floating weight pivotally connected to said support for rotation, a stylus bar disposed beneath said floating weight and having one end pivotally secured to said floating weight on an axis laterally displaced from the axis of said floating weight, a translating device, and a pivotal connection between said translating device and said stylus bar on a line substantially coincident with the axis of said floating weight.

5. In phonographic apparatus of the class described, a support, a floating weight pivotally secured to said support, a stylus bar having one end mounted on said floating weight at a point displaced from the point of connection of said weight to said support, a translating device comprising a vibratile member, and a link connected between said vibratile member and said stylus

55

bar, the connection between said link and stylus bar being pivotal and on a line substantially coincident with the axis of rotation of said weight.

6. In phonographic apparatus of the class described, a support, a floating weight pivotally secured to said support, a stylus bar having one end mounted on said floating weight at a point displaced from the point of connection of said weight to said support, a translating device comprising a vibratile member mounted on said support, and a link connected between said member, and the free end of said stylus bar, the connection between said link and said stylus bar being pivotal and on a line substantially coincident with the pivotal axis of said weight.

80

7. In phonographic apparatus of the class described, a translating device including a vibratile member, a stylus bar having a stylus intermediate its ends, a swingable support for one end of said stylus bar, said support having a high motional impedance to voice frequencies and a low motional impedance to frequencies below the range of voice frequencies, and a connection between the free end of said stylus bar and said vibratile member, said connection being pivotal and on a line substantially coincident with the axis of rotation of said swingable support.

90

8. Phonographic apparatus comprising a pivotally mounted floating weight, a stylus bar connected to said weight at a point offset from the pivotal axis of the latter, and means for connecting said bar to a translating device, said means having pivotal connection with said bar on a line substantially coincident with the pivotal axis of said weight.

100

9. Phonographic apparatus comprising a translating device, a pivotally mounted floating weight, and a stylus bar pivotally secured to said weight at a point offset from the pivotal axis of the latter, said bar having pivotal connection with said translating device on a line substantially coincident with the pivotal axis of said weight.

110

10. Phonographic apparatus comprising a translating device, a pivotally mounted floating weight, a stylus bar, and a link, said bar being pivotally connected at one end to said weight and at the other end to one end of said link, the other end of said link being connected to said translating device, the pivotal connection between said bar and said weight being offset from the pivotal axis of the latter and the connection between said bar and said link being on a line substantially coincident with the pivotal axis of said weight.
